US00D927689S

(12) **United States Design Patent** (10) **Patent No.:** **US D927,689 S**
(45) **Date of Patent:** **** Aug. 10, 2021**

(54) **THREE DIMENSIONAL MASTOPEXY
IMPLANT**

(71) Applicant: **Tepha, Inc.**, Lexington, MA (US)

(72) Inventors: **Skander Limem**, Melrose, MA (US);
Emily Stires, Boston, MA (US);
Rebecca Marcante, North Reading, MA (US); **Said Rizk**, Windham, NH (US); **Arikha Moses**, Summit, NJ (US); **Fabio Felix**, Foxborough, MA (US); **Bruce Van Natta**, Westfield, IN (US)

(73) Assignee: **Tepha, Inc.**, Lexington, MA (US)

(**) Term: **15 Years**

(21) Appl. No.: **29/735,098**

(22) Filed: **May 18, 2020**

(57) **CLAIM**

The ornamental design for a three dimensional mastopexy implant, as shown and described.

DESCRIPTION

FIG. 1 is a front view of a three dimensional mastopexy implant showing our new design;
FIG. 2 is a top view of the three dimensional mastopexy implant shown in FIG. 1;
FIG. 3 is a side view of the three dimensional mastopexy implant shown in FIG. 1;
FIG. 4 is a bottom view of the three dimensional mastopexy implant shown in FIG. 1;
FIG. 5 is another side view of the three dimensional mastopexy implant shown in FIG. 1;
FIG. 6 is a rear view of the three dimensional mastopexy implant shown in FIG. 1; and,
FIG. 7 is a top, front, side perspective view of the three dimensional mastopexy implant shown in FIG. 1.
